UNITED STATES PATENT OFFICE

2,435,364

GYRO TOP

Willie T. Pearson, Vicksburg, Miss.

Application November 1, 1945, Serial No. 626,081

1 Claim. (Cl. 46—70)

1

My invention as described herein, and illustrated in the accompanying drawings, consists of a toy top, an object of which is to provide a top so formed that it may be used in numerous ways.

Another object of my invention is to provide a disk top mounted upon a loose spindle upon which a cord is wound to spin the top.

A further object of this invention is to provide a top formed of a pair of disks fixedly mounted and spaced apart upon a common hub rotatable upon a spindle upon either end of which the top may spin.

Other features and advantages will become more readily apparent from the following description and the accompanying illustrative drawings in which:

Figure 1 is an elevational view of my improved top,

Figure 2 is a sectional view on line 2—2 of Figure 1.

While one embodiment of my invention is illustrated in the above referred to drawings, it is to be understood that it is merely for the purpose of illustration and that various changes in construction may be resorted to in the course of manufacture in order that the invention may be utilized to the best advantage according to circumstances which may arise, without in any way departing from the spirit and intention of my device, which is to be limited only in accordance with the appended claim. And while I have stated the primary field of utility of my invention it remains obvious that it may be employed in any other capacity wherein it may be found applicable.

In the accompanying drawings and in the following specification, the same reference characters are used to designate the same parts and elements throughout and in which 10 refers to my invention and 11 indicates a spindle which is projected loosely through an enlarged bore 12 through a hub 14 of a wheel 15 comprising a pair of spaced disks 16 and 17, said disks and hub being integral. Mounted on the ends 18 and 19 of the spindle 11 and fixed thereto are tubes 20 and 21 of substantially the length of the said ends 18 and 19. The outer terminals 22 and 23 of the members 19 and 21 are turned to a cone 24, while the similar ends 25 and 26 of the mem-

2

bers 18 and 20 are formed arcuate. There is a certain play or clearance space such as 27 between the terminals 28 and 29 of the members 20 and 21 and the walls 30 and 31 of the hub 14.

5 Due to the play of the shaft within the said hub 14 both laterally and longitudinally when the cord 32 is wound upon the hub between said disks and drawn rapidly off to rotate the wheel, the top when dropped upon either end 26 or 24 10 will spin with an irregular bouncing and gyrating movement. When the device is spinning on the cone 24, the top will spin much smoother than when on the end 26.

It is thought that persons skilled in the art to 15 which the invention relates will be able to obtain a clear understanding of the invention after considering the description in connection with the drawings. Therefore, a more lengthy description is regarded as unnecessary.

20 Changes in shape, size and rearrangement of details and parts such as come within the purview of the invention claimed may be resorted to, in actual practice, if desired.

Having now described my invention, that which 25 I claim as new and desire to procure by Letters Patent is:

In a top, the combination of a spindle having dissimilar shaped floor engaging ends, tubes fixed to the opposite ends of said spindle, and having their outer ends forming continuations of the spindle ends, an integrally formed hub and spaced parallel wheel discs loosely mounted on said spindle for axial and lateral movement with respect thereto, and said hub being adapted to receive 35 and support a winding cord.

WILLIE T. PEARSON.
